(57) **CLAIM**

The ornamental design for a watch case as shown and described.

DESCRIPTION

FIG. 1 is a front, right side, bottom perspective view of a watch case showing our new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof; and,
FIG. 8 is a reference front elevational view thereof, with a watchband attached.
The broken lines are included for the purpose of illustrating the environmental structure and form no part of the claimed design.
